UNITED STATES PATENT OFFICE.

JOHN J. MANNING AND JOHN W. STEPHENSON, OF TOLEDO, OHIO, ASSIGNEES TO THE NATIONAL MALLEABLE CASTINGS COMPANY, OF CLEVELAND, OHIO, A CORPORATION OF OHIO.

METHOD OF MAKING CASTINGS.

No. 922,792.

Specification of Letters Patent. Patented May 25, 1909.

Application filed January 15, 1907. Serial No. 352,393.

To all whom it may concern:

Be it known that we, JOHN J. MANNING and JOHN W. STEPHENSON, both of Toledo, Lucas county, Ohio, have invented a new and useful Method of Making Castings, of which the following is a description, reference being had to the accompanying drawing, forming part of this specification, in which—

10 Figure 1 is a side elevation of a casting produced in accordance with our invention; Fig. 2 is a top plan view, partly in horizontal section; and Fig. 3 is a perspective view, showing the inner face of the core by which 15 the inserts are supported.

A serious objection has been found in the use of journal boxes made of malleable cast iron when applied to pedestal trucks, in that the softness of the malleable iron causes it to 20 wear rapidly, and in a relatively short time the box must be taken out and scrapped. We have discovered means by which these difficulties can be overcome, and the journal box provided with a durable wearing face 25 which will enable it to outlast the ordinary malleable box and does not entail any objectionable features in the way of expense or difficulty of manufacture.

In the drawing, 2 represents a journal box 30 of malleable cast iron having, on its sides, vertical grooves 3—3 for the pedestals of the truck. In casting this box, we employ a core such as shown in Fig. 3, which is made of baked sand or suitable core-making material and having vertical projections 3' which are counterparts of the grooves to be produced. Before assembling this core in the mold, we set on the projections 3' U-shaped pieces or clips of steel 4—4, which embrace 35 the sides of the projections, to constitute facings therefor. These pieces are not continuous along the length of each projection, 40 3', but are discontinuous, so that their presence will not cause the rupture of the casting 45 when it shrinks. The core to which the pieces 4 have been applied in this manner is then assembled in the mold, and when the molten metal is cast it will surround the pieces 4 and will embed them therein, in the 50 manner shown in Fig. 2 of the drawing so as to produce pedestal grooves having facing pieces of steel which, being much more durable and less abradable than malleable cast

iron, will insure a much longer period of usefulness to the box. When the casting cools, 55 the shrinkage of the metal effectually retains the facing pieces in place without the employment of extraneous fastening means.

We claim:

1. The method herein described of making 60 castings with hard metal facings, which consists in applying to a core having projecting portions adapted to form grooves in the castings separated pieces of a desired facing metal, then casting the molten metal against 65 the same, and permitting the casting to shrink upon the metal facings to hold the same in place.

2. The method herein described of making 70 castings with hard metal facings, which consists in applying to a core having projecting portions adapted to form grooves in the castings separated substantially U-shaped pieces of a desired facing metal, then casting 75 the molten metal against the same, and permitting the metal to shrink upon the facings to retain the same in place.

3. A casting having a lateral groove and separated inset pieces of hard metal spaced along the groove and held in place by the 80 shrinkage of the molten metal.

4. A casting having a lateral groove and separated inset, U-shape pieces of hard metal spaced along the groove and held in place by the shrinkage of the molten metal. 85

5. The herein described method which consists in applying a facing piece to a core, casting molten metal against the same, and permitting the molten metal to cool and shrink upon the facing piece and thereby re- 90 tain the piece in the casting.

6. The herein described method which consists in forming a core having a rib de- 95 signed to form a groove in the casting, applying a metal facing element to the rib, casting molten metal against the same, and permitting the molten metal to cool and shrink upon the facing piece and thereby re- tain the piece in the casting.

In testimony whereof, we have hereunto 100 set our hands January 11th, 1907.

JOHN J. MANNING.

JOHN W. STEPHENSON
